UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed August 23, 1919. Serial No. 319,309.

To all whom it may concern:

Be it known that I, ALBEN E. LUNDELL, a citizen of the United States, residing at New York, in the county of Bronx, State of New York, have invented certain new and useful Improvements in Telephone-Exchange Systems, of which the following is a full, clear, concise, and exact description.

This invention relates to telephone exchange systems, and more particularly to registering systems for automatic or semi-automatic telephone exchanges.

An object of the present invention is to control selection of a called line according to a system of numbering different from the system used for designating the called line.

A further object of the invention is to provide means for convenient changes in the method of selecting called lines without reference to or change in their numerical designations.

This is accomplished by making use of a selecting mechanism and a further object of the invention provides simple and inexpensive means for setting the selecting mechanism upon the selected point.

Although the annexed description and drawings show a semi-automatic system, it is understood that the scope of the invention is not determined by the particular structure disclosed, reference being had to the appended claims for that purpose.

In the drawings, Fig. 1 represents a calling subscriber's line, a connecting circuit, and a selector switch; Fig. 2 (to be placed to the right of Fig. 1) a connector switch adapted to seize a called subscriber's line; and Fig. 3 (which is to be placed below Fig. 1) a selector controlling apparatus; and a registering apparatus by means of which the selector controlling apparatus and in turn the selector and connector switches may be set.

The selector and sequence switches will not be disclosed in full in the following description of this system, since switches of this type are well-known in the art. A complete description of such switches may be obtained from Patent No. 1,168,319, patented January 18, 1916, to A. E. Lundell.

When the calling subscriber at station 100 desires to obtain a connection with another subscriber, as, for example, station 200, he removes his receiver from the switch-

hook and closes thereby a circuit for line 55 relay LR, which in turn lights a calling lamp CL. The operator upon noticing lamp CL lighted, inserts plug 101 into jack 102 in which the calling line terminates, whereupon a circuit is closed from grounded battery, through the winding of cut-off relay CR, sleeve contacts of jack 102 and plug 101, and the winding of relay 103 to ground. Relay 103 closes a circuit from ground, through the armature and front contact of relay 103, contact 104 and power magnet of sequence switch 105 to ground battery. Normal spring 106 controls the movement of sequence switch 105 through to position 2. A circuit is now closed from ground, sequence switch contact 107, conductor 108, contact 300 of sequence switch 301, the winding of relay 302 to grounded battery. The energization of the relay 302 closes a circuit from ground, left-hand armature and front contact of relay 302, contact 303, and the power magnet of sequence switch 301 to grounded battery. Normal spring 304 controls the movement of sequence switch 301 through to position 2. Although the energizing circuit of relay 302 becomes broken at contact 300 upon the movement of sequence switch 301 out of position 1, relay 302 does not deenergize, a circuit for holding it energized being closed from grounded battery, winding of relay 302, sequence switch contact 305, right-hand armature and front contact of relay 302, conductor 306, and contact 109 of sequence switch 105 to ground.

The operator depresses her listening key 110 and thereby connects her telephone set 111 to the connecting circuit and to the calling subscriber's line, establishing a conversational circuit to him and, in accordance with instructions, adjusts the registering apparatus provided for registering the numerical designation of a called subscriber. Only two sets of register keys are shown in the upper right-hand corner of Fig. 3, as it is thought to be sufficient for the purpose of describing the present invention to describe the setting of interconnecting means 112 and connecting means 201 respectively in accordance with two digits of the called subscriber's number. It will be obvious to those skilled in the art that these switches or a greater number of switches may be set

by means of other digits of the numerical designation of the called subscriber's line.

It will also be obvious to those skilled in the art that the jack-plug connection at 5 102 and 101 can be replaced by well-known line-finding means and that by providing at substation 100 a well-known calling dial the registering keys 401, 402 and 403 can be replaced by switches of the step-by-step type, 10 thereby converting the system from the semi to the full automatic type. Such mechanically operated registers might be of the type shown in the patent to Polinkowsky 15 1,193,053, issued August 1, 1916.

Assuming that the designation of the called subscriber's line is such as to cause the registering device 401 to be set in such a position—there being several other positions—as to open contact 403, instead of one of the 20 other contacts, which are opened when the device is set in such other positions; and to set registering device 402 to open contact 404, the operation of starting device 405 closes the following circuit: ground, sequence-switch contact 310, starting contact 405, right-hand winding of relay 406 to grounded battery. The energization of relay 406 closes a circuit from ground, left-hand armature and front contact of relay 30 406, conductor 407, sequence switch contact 311, and power magnet of sequence switch 301 to grounded battery. The movement of sequence switch 301 from position 2 through to position 3 is controlled by normal spring 304. A circuit is now closed for up-drive magnet 408 from grounded battery, up-drive magnet 408, sequence switch contact 322, conductor 407, left-hand front contact and armature of relay 406 to ground. Relay 406 has remained in its operated position by virtue of the closure of the following circuit: grounded battery, right-hand winding, front contact and armature of relay 406, commutator segment 409, and commutator brush 410 to ground. Relay 406 is provided with a second winding 411 by means of which the electrical condition of the two rows of terminals 412 and 413 are tested in turn as the movable brushes 415 and 414 come into contact therewith.

The row of terminals 412 is arranged in groups, there being as many terminals in each group as there are points in the registering device 402, and as many groups as there are points in registering device 401.

The row of terminals 413 are also arranged in groups and the corresponding terminals of each group are connected together. For example, the first terminals of each group are connected together and to the first point 416 of registering device 402, the second terminals of each group are connected together and to the second point 422 of registering device 402 and so on. It will be seen therefore, that there can be provided as

many terminals in the translator device 417 as the product of the number of points in registering device 401 multiplied by the number of points in registering device 402. Assuming that contact 403 has been opened 70 as a result of the operation of registering device 401, and that contact 404 has been opened by the operation of registering device 402, the upward movement of translator 417 is stopped only when brushes 414 75 and 415 contact with terminals in the second group and specifically the sixth terminal of the second group, since the left-hand winding of relay 406 finds a closed circuit when the brushes 414 and 415 contact with any 80 terminals previous to those mentioned. Since the electrical condition set up at the time the brushes contact with one of these previous sets of terminals is different from that set up at another previous terminal, for 85 the sake of brevity only two of these cases will be described in detail. It may be readily understood that the other conditions are similar, the only differences being in regard to the particular wiring contact and terminal numbers. When, for example, the brushes 414 and 415 are in engagement with the first terminal of the first group, a circuit is closed from ground, contact 416 of 90 registering device 402, conductors 418 and 419, brush 414, to the test winding 411 of relay 406. Another circuit is closed from ground, contact 420 of registering device 401, conductor 421, brush 415 to relay 406. When, for example, brushes 414 and 415 are 95 in engagement with the second terminal of the first group, the following circuit is closed: ground, contact 422 of registering device 402, conductor 423, brush 414, to test winding 411 of relay 406. It will be seen, 100 therefore, that the test relay 406 cannot de-energize until brushes 415 and 414 are in engagement with the open contacts of registering devices 401 and 402 respectively, and the commutator brush 410 reaches an insulated 105 segment of the commutator contact 409.

Upon the release of relay 406, the circuit of the up-drive magnet 408 is opened, causing the brushes of the translator device 417 to come to rest, and closing the following 115 circuit: ground, left-hand armature and back contact of test relay 406, sequence switch contact 313, and power magnet of sequence switch 301. The sequence switch 301 is moved through to position 4 by normal 120 spring 304.

A fundamental circuit is now closed from grounded battery, through winding of relay 113, sequence switch contact 114 (sequence switch 105 being still in position 2 as described above), conductor 115, sequence switch contact 314, outer armature and back contact of counting relay O', winding of stepping relay 315, conductor 316, sequence switch contact 116 to ground. Relays 113 and 130

315 become energized. Relay 113 closes the following circuit: ground, right-hand armature and front contact of relay 113, sequence switch contact 117, conductor 118, power magnet of sequence switch 105 to grounded battery, for moving this sequence switch into position 3. Relay 113 remains energized in spite of the opening of sequence switch contact 114 because of the closure of 5 an alternate path through its left-hand armature and front contact and the sequence switch contact 119. Upon the energization of relay 315, a circuit is closed from ground, front contact and armature of relay 315, sequence switch contact 317, conductor 318, brush 424, stationary contact 425, conductor 426, conductor 427, conductor 332, the armature and back contact of the No. 9' counting relay, winding of counting relay 9, to 10 grounded battery. The counting relay 9 closes a circuit from ground, through sequence switch contact 320, conductor 321, armature and front contact of counting relay 9, winding of counting relay 9', winding 15 of counting relay 9 to grounded battery. Counting relay 9' cannot become energized, however, because of a short-circuit around its winding, there being a direct ground on its armature and back contact which originated at the front contact of stepping relay 315 as described above. A circuit is also closed for the up-drive magnet 120 of selector switch 112 by way of sequence switch contact 121 and right-hand front contact 20 and armature of relay 113. The energization of magnet 120 attracts armature 122, pressing brush rod 123 against the constantly driven roller 124. This imparts an upward motion to the brush rod 123 and 25 drives selector wipers 124, 125, 126, and commutator brushes 127 and 128 in an upward direction. Wipers 124, 125 and 126 come into contact with corresponding rows of stationary terminals such as shown, and 30 commutator brushes 127 and 128 traverse the conducting and insulated segments of commutator plate 130. When the commutator brush 128 contacts with a conducting segment 131, ground is connected through 35 the segment, conductor 132, sequence switch contact 133, to the conductor 115, thereby short-circuiting relay 315, the other side of the winding of which is also connected to the ground at sequence switch spring 116. 40 Relay 315 opens at its front contact the short-circuit around the No. 9' counting relay, permitting the energization of this relay, and conductor 332 becomes connected by way of the armature and front contact 45 of the No. 9' counting relay to the armature and back contact of the No. 8' counting relay. The arrangement of the No. 8' counting relay and its mate, the No. 8 relay, as 50 well as the remaining pairs of counting relays is similar to that of the No. 9' and No. 55 9 counting relays previously described. When the commutator brush 128 leaves conducting segment 131, relay 315 is again energized. This in turn operates counting relay 8 which accordingly connects into circuit the No. 8' counting relay but the latter cannot operate because of a short-circuit corresponding to the one described for the No. 9' relay previously. In substantially 60 the same manner the remainder of the counting relay chain cooperates with the opening and closure of the ground at commutator brush 128, as the brush rod continues its upward motion over the insulated and conducting segments, until after 10 65 steps, when the 0' counting relay becomes energized. This opens the fundamental circuit, including the windings of relay 315 and 113, and closes the following circuit: ground, sequence switch contact 324, inner armature and front contact of the 0' counting relay, power magnet of sequence switch 301, to grounded battery, thereby causing the movement of the sequence switch out of 70 position 4, and because of the normal spring 304 into position 6. The duration of the opening of the sequence switch contact 320 between positions 4 and 6 is sufficient to release all of the counting relays which have 75 been locked up in the selecting operation just described. 80 As a result of the operation of the 0' counting relay and of the engagement of the commutator brush 128 with an insulated segment, relay 113 releases and closes the 85 following circuit: ground, right-hand armature and back contact of relay 113, sequence switch contact 135, conductor 118 and the power magnet of sequence switch 105 to 90 grounded battery, moving the sequence switch into position 6. It will be noted that the release of relay 113 also opens the circuit of the up-drive magnet 120, thereby 95 stopping the brushes in their displaced position. 100 When the sequence switch reaches position 6, a circuit is closed from ground, sequence switch contact 136, right-hand winding of relay 138, to grounded battery, for 105 energizing relay 138. 110 The operation of relay 138 closes a circuit from ground, through the right-hand armature and front contact of relay 138, sequence switch contact 140, conductor 118, and the power magnet of sequence switch 105 to grounded battery, whereupon the sequence switch moves into position 7. If the trunk first reached were busy, when the energizing circuit of relay 138 became open 120 at sequence switch contact 136, this relay would be maintained energized, because of a circuit consisting of the left-hand winding, middle front contact and armature of 125 this relay, conductor 152 to the test contact of the busy trunk. 130

The up-drive magnet 120 would then be energized because of the closure of the following circuit: ground, right-hand armature and front contact of relay 138, sequence switch contact 145, up-drive magnet 120, to grounded battery. When the wipers 124, 125 and 126 reach the terminals of an idle trunk, and let us say now that trunk 202, 203 and 204 is the first idle trunk, no ground circuit will be available for holding energized the left-hand winding of relay 138 so that when the commutator brush 127 engages an insulated segment 141 of the commutator plate 130, relay 138 becomes deenergized and opens the circuit of magnet 120. The upward movement of the brush rod 123 is thereby arrested and the wipers 124, 125 and 126 remain in engagement with the terminals connected to trunk conductors 202, 203 and 204.

The release of relay 138 closes a circuit by way of sequence switch contact 146, conductor 118, power magnet of sequence switch 105 to grounded battery, moving the sequence switch out of position 7 and into position 11. Sequence switch 301 is now in position 6 as previously described, and sequence switch 205 is in position 1, since it was assumed that trunk 202, 203 and 204, which terminates in the selector 201 and sequence switch shown in Fig. 2 was idle, that is in the normal position.

A new fundamental circuit is now closed as follows: grounded battery, winding of relay 207, sequence switch contact 208, trunk conductor 202, wiper 124 of selector 112, sequence switch contact 150, conductor 115, sequence switch contact 314, outer armature and back contact of the 0' counting relay, winding of stepping relay 315, conductor 316, sequence switch contact 151, wiper 125 of the selector 112, trunk conductor 203, and sequence switch contact 209 to ground.

Relay 207 closes a circuit from ground, through its right-hand armature and front contact, contact 210, and the power magnet of sequence switch 205 to grounded battery, and this sequence switch is thereupon moved into position 2. The relay 207 locks up through its left-hand front contact and armature and sequence switch contact 211 independent of contact 208, and thus will not become deenergized when the sequence switch 205 leaves position 1 and contact 208 becomes opened. In position 2 of sequence switch 205 a circuit is closed from ground, through sequence switch contact 212, the winding of relay 206 to grounded battery, and this relay upon operating closes a circuit from ground, through its right-hand armature and front contact, contact 213 and the power magnet of sequence switch 205 to grounded battery, whereupon this sequence switch is moved into position 3. Relay 206,

although its energizing circuit is opened at contact 212 when the sequence switch moves as described, does not deenergize due to the continued closure of the following circuit: ground, sequence switch contact 153 of Fig. 1, back contact and middle armature of relay 138, conductor 152, brush 126, conductor 204, left-hand armature and front contact of relay 206 of Fig. 2, through the winding of this relay to grounded battery.

The up-drive magnet 215 of connector 201 is now energized by way of a circuit originating at the right-hand armature of relay 207, right-hand front contact of this relay, sequence switch contact 216, up-drive magnet 215, to grounded battery. The armature 217 is accordingly attracted and presses brush rod 218 against constantly driven roller 219, thereby causing the connector switch wipers 220, 221, 222, and commutator brush 223 to move in an upward direction. The wipers mentioned traverse a contact bank in which called lines terminate, the commutator brush 223 contacting with conducting and insulated segments, such as 225 and 226, of the commutator plate 227. As a result of the energization of relay 315 which occurred when the new fundamental circuit including relay 207 was closed, a circuit is now closed from ground, through the front contact and armature of relay 315 of Fig. 3, sequence switch contact 330, conductor 331, wiper 428, terminal 429 of translator 417, conductor 430, conductor 431, conductor 432, armature and back contact of No. 3' counting relay, winding of No. 3 counting relay to grounded battery. The counting relay chain under control of stepping relay 315, operates in substantially the same manner as previously described. The short circuits for the stepping relay are caused by the closure of a circuit from ground, through commutator brush 223, conducting segment 225, conductor 230, sequence switch contact 231, to the conductor 202, which is, as previously described, connected through to the stepping relay 315, and the current from the grounded battery through the winding of relay 207 now flows to ground at commutator brush 223. After four impulses have been counted off (conductor 431 having been connected to the No. 3 pair of counting relays) the 0' counting relay opens the fundamental circuit at its outer armature and when commutator brush 223 passes off of conducting segment 225, relay 207 becomes deenergized. The 0' counting relay also closes a circuit from ground, through sequence switch contact 324, the inner armature and front contact of the 0' counting relay through the power magnet of sequence switch 301 to grounded battery, for moving the sequence switch out of position 6, which because of the normal spring 304 continues into position 16.

It will be noted that conductor 431, as well as conductor 427, are part of a cross-connecting rack and that they are employed as jumpers from the first section 441 to the second section 442 of the connecting rack 443. By means of this connecting rack the number of impulses to be transmitted over the fundamental circuit 115 and 316 can be changed at will in a simple and efficient manner.

A circuit is then closed from ground, through sequence switch contact 335, conductor 336, contact 155 and the power magnet of sequence switch 105 to grounded battery, and sequence switch 105 is accordingly moved out of position 11, and because of normal spring 106 moves into position 16. As soon as sequence switch 105 moves out of position 11, contact 109 of this sequence switch is opened and relay 302 becomes de-energized. A circuit is thereupon closed from ground, through the left-hand armature and back contact of relay 302, contact 337, and the power magnet of sequence switch 301 to grounded battery for moving this sequence switch out of position 16 into position 18. In positions 17 and 18 of sequence switch 301, contact 333 closes a circuit from ground to release magnets 433, 434 and 440, through these release magnets to grounded battery, and the energization of the release magnets restores the associated registering devices to normal. In position 18 of sequence switch 301 a circuit is closed from sequence switch contact 334 to conductor 338 to the down-drive magnet 435 of the translator 417, causing the brush rod 436, the wipers 414, 415, 424, 428, and the commutator brushes 410 and 437 to be moved in a downward direction. When commutator brush 437 strikes conducting segment 438 a circuit is closed from ground, commutator brush 437, conducting segment 438, conductor 439, sequence switch contact 337, and power magnet of sequence switch 301 to grounded battery, moving sequence switch 301 out of position 18 and into its normal position 1. The opening of sequence switch contact 334 deenergizes down-drive magnet 435. It will be noted that the selector controlling apparatus, the translator 417, and the registering devices of Fig. 3 are now fully restored to their normal position and ready to be used on the next call.

Upon the deenergization of relay 207 of Fig. 2, the circuit of the up-drive magnet 215 is broken, and the wipers are stopped in their displaced position. The following circuit is now closed: ground, right-hand armature and back contact of relay 207, sequence switch contact 232, and power magnet of sequence switch 205 to grounded battery for moving this sequence switch out of position 3 into position 13. After the testing of the selected line in accordance

with any well-known manner of testing such lines, a ringing circuit is closed from ringing current source 234, through the winding of relay 235, sequence switch contact 236, wiper 221, the called substation circuit, wiper 220 and sequence switch contact 237 to ground. Relay 235 is marginal and does not operate upon the relatively small current which is permitted to flow through the condenser at the called station, but upon the removal of the receiver the current flow is increased and the marginal relay 235 becomes operated, thereby closing the following circuit: ground, sequence switch contact 238, the front contact and armature of relay 235, the power magnet of sequence switch 205 to grounded battery. Sequence switch 205 is moved out of position 13 and into position 16. The movement of the sequence switch out of position 13 necessarily releases marginal relay 235. The calling and called subscriber are now telephonically connected, the talking circuit being indicated by relatively heavy lines in Figs. 1 and 2.

Upon completion of the conversation the subscribers replace their receivers on the switchhooks and cause in a well-known manner the actuation of supervisory devices 160 and 161, together with any local signals which it may be desirable to place under the control of these devices. The operator upon noticing the actuation of these signals removes the plug 101 from jack 102, whereupon cut-off relay CR and relay 103 are released. In the case of a full automatic exchange, the train of switches including the line finding means, is restored when the subscribers replace their receiver, in a manner well-known in the art; and accordingly relays CR and 103 are released. A circuit is then closed from ground, through the armature and back contact of relay 103, sequence switch contact 162, the power magnet of sequence switch 105 to grounded battery, whereupon this sequence switch is moved out of position 16 and into position 18. In this last-mentioned position a circuit is closed from ground, sequence switch contact 164, down-drive magnet 163, to grounded battery, and armature 165 upon becoming attracted causes the restoration of brush rod 123 in a downward direction. Upon reaching its normal position a circuit is closed by way of commutator brush 127, conducting segment 167, which is closed only at the normal position, conductor 168, sequence switch contact 169, conductor 118, the power magnet of sequence switch 105, to grounded battery, moving this sequence switch out of position 18 and into normal position 1. When the sequence switch leaves position 18 magnet 163 becomes deenergized.

Relay 206 of Fig. 2 is released as a result of the opening of sequence switch contact 153, which occurred when sequence

switch 105 moved from position 16 to 18. A temporary "make busy" circuit is closed from ground, through sequence switch contact 240, through the left-hand back contact 5 tact and armature of relay 206 to conductor 204 for maintaining the busy test condition on the multiple bank terminal connected thereto during the period that connector switch 201 is being restored. In consequence of the release of relay 206 a circuit is closed from ground, right-hand armature and back contact of this relay, sequence switch contact 241, power magnet of sequence switch 205 to grounded battery, 10 causing the movement of this sequence switch out of position 16 and into position 18. This in turn closes a circuit from ground, through sequence switch contact 242 closed in position 18, winding of down-drive magnet 243 to grounded battery. The energization of down-drive magnet 243 causes the restoration of connector 201 to the normal position. When commutator brush 223 contacts with conducting segment 244, a circuit is closed from ground, through commutator brush 223, conducting segment 244, conductor 245 and contact 246 through the power magnet of sequence switch 205 to grounded battery for moving this sequence 15 switch out of position 18 and into its normal position 1. The opening of sequence switch contact 242 releases down-drive magnet 243 and the opening of contact 240 permits the trunk 202, 203, 204 to be again seized for a 20 subsequent call. It will be seen from the above description that the apparatus of Fig. 1 and of Fig. 2 has now been restored to the normal position and is available for use again.

40. What is claimed is:

1. In a telephone exchange system, a selector switch, a control relay therefor, a branched circuit for said relay extending to movable contacts of said switch, a plurality of normally closed extensions of each branch of said circuit extending from stationary contacts of said switch, and means for selectively opening any one of the circuit extensions of each branch to jointly 45 direct the movement of said switch under the control of said relay.

2. In a telephone exchange system, a selector switch, a control relay therefor, a branched circuit for said relay extending to 50 movable contacts of said switch, a plurality of normally closed extensions of each branch of said circuit extending from stationary contacts of said switch, and means for simultaneously and selectively opening an extension of each branch of said circuit to jointly direct the movement of said switch under the control of said relay.

60. 3. In a telephone exchange system, a selector switch, a test relay for controlling the movement of said switch, a branched

circuit for said relay extending to movable contacts of said switch, a plurality of extensions of said circuit extending from stationary contacts of said switch, and means for selectively controlling the circuit extensions of said branches in varying combinations to direct the movement of said switch under the control of said test relay.

70. 4. In a telephone exchange system, a selector switch, a plurality of test circuits arranged in groups, means for selectively altering the test condition in any circuit in each of said groups, and means for testing circuits in all of the groups simultaneously and for advancing said switch to a point jointly predetermined by the test condition in the circuits selectively altered.

75. 5. In a telephone exchange system, a selector switch having a plurality of testing positions, a multiple test circuit with branches, a plurality of normally closed contact devices for each of said branches, means for causing the advance of said switch, means for simultaneously connecting a number of branches of said test circuit to a corresponding number of contact devices, and means for stopping said switch upon reaching a resting position in which all branches of the test circuit are opened.

80. 6. In a telephone exchange system, a selector switch having a plurality of resting positions, a multiple test circuit with branches, a plurality of normally closed contact devices for each of said branches, means for simultaneously connecting a 90 number of branches of said test circuit to a corresponding number of contact devices, means for advancing said switch whenever the test circuit includes one or more closed contact devices, and means for stopping said switch upon reaching a resting position in which all branches of the test circuit are opened.

95. 7. In a telephone exchange system, a selector switch having a plurality of resting positions, a multiple test circuit with branches, a plurality of normally closed extensions for each branch of said circuit, means for advancing said switch and for associating each of said branches with the 100 extensions thereof, means for opening any of said extensions and means for arresting said switch when each branch of said test circuit becomes associated with an open extension thereof, the number of resting positions being equal to or less in number than the product of the number of extensions in all branches.

110. 8. An electrical system for selecting terminals comprising an apparatus having registers corresponding to groups of some numerical system, a translator controlled by said register, a selector controlling apparatus for effecting the selection of terminals in accordance with a numerical group dif- 115

ferent from that first named, and means for altering the relation between said translator and selector controlling apparatus.

9. A translating system comprising a translator set in accordance with the setting of one or more registering devices for transmitting impulses in a predetermined group or groups, and means for shifting the control of said impulses by said translator.

10. In a telephone exchange system, a selector switch, means for controlling the advance of said switch, a plurality of groups of testing terminals, wipers associated with said switch for simultaneously connecting terminals in all of said groups with said controlling means, a source of testing potential normally connected to all of said terminals and means comprising registering devices for selectively disconnecting said potential from a terminal of each group, whereby said switch may be selectively positioned in accordance with said operated registering devices.

11. In a telephone exchange system, a selector switch, means for controlling the advance of said switch, a plurality of groups of testing terminals, each of said groups being divided into a plurality of subgroups, wipers associated with said switch for simultaneously connecting terminals in all of said groups with said controlling means, a source of testing potential normally connected to all of said terminals and means comprising registering devices for selectively disconnecting said potential from the terminals of any sub-group of one of said groups and from any terminal of one of the sub-groups of another of said groups, whereby said switch may be positioned in accordance with said operated registering devices.

12. In a telephone exchange system, switching mechanism, a plurality of registering devices for recording the designations of desired lines, means controlled by said registering devices for controlling said switching mechanism to extend connections to said desired lines, and means comprising a cross-connecting rack associated with said

registering devices and said control means adapted to be readily changed to modify the control of said switching mechanism by said registering devices.

13. In a telephone exchange system, switching mechanism, a plurality of registering devices for recording the designations of desired lines, means controlled by said registering devices for controlling said switching mechanism to extend connections to said desired lines, and a cross connecting rack interposed between said registering devices and said control means having jumper connections adapted to be readily changed to modify the control of said switching mechanism by said registering devices.

14. In a telephone exchange system, switching mechanism, a plurality of registering devices for recording the designations of desired lines, a translator switch, means for setting said switch into a position jointly determined by said registering devices, means for controlling said switching mechanism to extend connections to said desired lines and means interposed between the bank terminals of said switch and said control means adapted to be readily changed to modify the control of said switching mechanism by said registering devices.

15. In a telephone exchange system, switching mechanism, a plurality of registering devices for recording the designations of desired lines, a translator switch, means for setting said switch into a position jointly determined by said registering devices, means for controlling said switching mechanism to extend connections to said desired lines, and a cross connecting rack interposed between the bank terminals of said switch and said control means adapted to be readily changed to modify the control of said switching mechanism by said registering devices.

In witness whereof, I hereunto subscribe my name this 21st day of August, A. D., 1919.

ALBEN E. LUNDELL.
